FIG III

FIG II

FIG IV

FIG. V

INVENTOR
SAMUEL McFARLAND,

BY
John C. Page
ATTORNEY

UNITED STATES PATENT OFFICE.

SAMUEL MCFARLAND, OF COATESVILLE, PENNSYLVANIA.

CASTING APPARATUS.

Application filed December 27, 1921. Serial No. 525,126.

To all whom it may concern:

Be it known that I, SAMUEL MCFARLAND, a citizen of the United States, residing at Coatesville, Pennsylvania, have invented a 5 certain new and useful Improvement in Casting Apparatus, whereof the following is a specification, reference being had to the accompanying drawing.

My improvement is particularly applicable to internal stoppers for bottom-pour ladles, such as are used for casting steel. Ordinarily, such a stopper consists of a head of refractory, and incidentally frangible, material, such as graphitic cement, 10 having means to engage a stopper rod, by which said head may be raised and lowered, within the ladle, to open and close a nozzle outlet at the bottom of the ladle. The strain upon such frangible material incident to repeatedly reciprocating said rod, of course tends to loosen and detach said head and thus permit the accidental escape of 15 the molten steel, with consequent loss and damage.

It is an object of my invention to so construct and arrange a stopper head of such frangible material that it is impossible to separate it from the stopper rod by any stresses to which it may be subjected during 20 the ordinary operation of the apparatus. To that end; I provide a stopper head molded of graphitic cement or other suitable refractory material with a bifurcated metallic shank permanently and rigidly imbedded therein, and provide such shank with means to detachably engage the stopper rod.

My invention includes the various novel features of construction and arrangement 25 hereinafter more definitely specified.

In said drawing; Fig. I is a plan view of a convenient embodiment of my invention.

Fig. II is an elevation of the structure 30 shown in Fig. I.

Fig. III is a plan sectional view taken on the line III-III in Fig. II.

Fig. IV is an elevation of said structure 35 shown in Fig. II; but at right angles to that view, and with a part of the stopper-head shown in section.

Fig. V is a plan view of a stopperhead embodying my invention, but having a modified form of shank imbedded therein.

50 In said figures; the stopperhead 1 is

molded of non-metallic refractory material, such as graphitic cement, and in rigid connection with a bifurcated stopper shank 2, which is conveniently formed of a rectangular wrought iron bar bent to U-shape, 60 as best shown in Fig. IV. The bifurcated ends 3 of said shank 2 extend above the conical neck 4 on said head 1, and are there provided with opposite coaxially aligned holes 5 which may be drilled or 65 punched. Said head is so molded in the bight of said shank 2 as to form a socket 7 for the end of the stopper rod 8 which is provided with the cylindrical hole 9 to receive the cross pin 10 which is detachably 70 fitted in said shank holes 5, as shown. As shown in Figs. I and II, said stopper rod 8 is preferably made of less width than said socket 7, so as to permit a slight amount of play of said head 1 on said rod 8 to 75 enable the head to automatically accommodate itself to the nozzle opening.

The provision of said neck 4 upon said head 1 is advantageous in that it protects the metallic shank and end of the stopper 80 rod at a region that might be accidentally melted off, if not thus protected, as such accidents frequently occur with stopper-heads of the ordinary form devoid of such a protecting neck.

As is well-known to those skilled in this art; such stopper rods are usually provided with protecting sleeves 13 formed of graphitic cement, ganister, or other suitable refractory sheathing material, and I prefer 90 to form an annular groove 15 in the top of said stopper head 1 to receive the lower end of the protecting sleeve 13 as shown in Fig. IV. However, the weight of such sheathing material 13 is supported independently of said head 1 by the upper ends 3 of said shank 2 which are connected with said stopper rod 8 by the pin 10, as above described.

Although I have shown the stopper rod 100 8 as a single piece directly connected with said shank 2 as above described; such a rod is approximately twelve feet long and, whenever its end, adapted for engagement with the shank, becomes damaged, it would be 105 more troublesome to transport it to and from the place where it must be repaired, and to effect such repairs, than to manipulate a shorter piece. Therefore, it is advantageous to form such a rod in sections which may be 110

coupled in any convenient manner, and I do not desire to limit myself to the specific details of construction and arrangement thereof, which are not essential to the operation of my invention.

Of course, such stopperheads must be of different sizes and shapes, to fit the various forms of ladle outlet nozzles. Moreover, it is to be understood that the shank, imbedded 10 in the stopperhead in accordance with my invention, may be shaped otherwise than as shown. For instance, it may be made of what is known commercially as "half round bar", with its rounded surfaces presented 15 outwardly and thus afford a greater thickness of the refractory material in the neck, as indicated in Fig. V, as compared with the rectangular bar shown in Fig. III, the outer edges of which project to such a degree 20 as to reduce the thickness of the refractory material in the neck.

Although I prefer to form shanks of wrought iron or steel, bent as above described, of course, they may be formed of 25 cast metal. Therefore, I do not desire to limit myself to the precise details of construction and arrangement herein set forth, as it is obvious that various modifications 30 may be made therein, without departing from the essential features of my invention, as defined in the appended claims.

I claim:

1. In casting apparatus, the combination 35 with a stopper-head, of non-metallic refractory material, such as graphitic cement, provided with a conical neck and having an annular groove at the junction of said head and neck; of a metallic stopper shank including a U-shaped body having its bight imbedded in said head and its bifurcated ends 40 projecting therefrom, through said neck; said bifurcated ends being provided with transversely extending holes in coaxial relation exterior to said neck; the refractory 45 material of said head being recessed between the bifurcations of said shank, to form a stopper rod socket within said neck; a stopper rod detachably fitted in said socket, having a transversely extending hole in coaxial 50 relation with the holes in said shank; and a cross pin extending in the holes of said shank and stopper rod, detachably connecting them in cooperative relation.

2. In casting apparatus, the combination 55 with a stopper-head, of non-metallic refractory material, provided with a neck and having an annular groove at the junction of said head and neck; of a metallic stopper shank including a U-shaped body having its bight imbedded 60 in said head and its bifurcated ends projecting therefrom, through said neck; said bifurcated ends being provided with transversely extending holes, in coaxial relation; the refractory material of said 65 head being recessed between the bifurcations

of said shank, to form a stopper rod socket within said neck; a stopper rod detachably fitted in said socket, having a transversely extending hole in coaxial relation with the holes in said shank; and a cross pin extending in the holes of said shank and stopper rod, detachably connecting them in cooperative relation. 70

3. In casting apparatus, the combination 75 with a stopper-head, of non-metallic refractory material, provided with a neck; of a metallic stopper shank including a U-shaped body having its bight imbedded in said head and its bifurcated 80 ends projecting therefrom, through said neck; said bifurcated ends being provided with transversely extending holes, in coaxial relation; the refractory material of said head being recessed between the bifurcations of said shank, to form a stopper rod socket within said neck; a stopper rod detachably fitted in said socket, having a transversely extending hole in coaxial 85 relation with the holes in said shank; and a cross pin extending in the holes of said shank and stopper rod, detachably connecting them in cooperative relation. 90

4. In casting apparatus, the combination 95 with a stopper-head, of non-metallic refractory material; of a metallic stopper shank including a U-shaped body having its bight imbedded in said head and its bifurcated ends projecting therefrom; said bifurcated ends being provided with transversely extending holes, in coaxial relation; the refractory material of said head being recessed 100 between the bifurcations of said shank, to form a stopper rod socket; a stopper rod detachably fitted in said socket, having a transversely extending hole in coaxial relation with the holes in said shank; and a cross pin extending in the holes of said shank and stopper rod, detachably connecting them in cooperative 105 relation.

5. In casting apparatus, the combination 110 with a stopper-head, of non-metallic refractory material; of a metallic stopper shank including a U-shaped body having its bight imbedded in said head, and having transversely extending holes, in coaxial relation; the refractory material of said head being recessed 115 between the bifurcations of said shank, to form a stopper rod socket; a stopper rod detachably fitted in said socket, having a transversely extending hole in coaxial relation with the holes in said shank; and a cross pin extending in the holes of said shank and stopper rod, connecting them in cooperative 120 relation.

6. In casting apparatus, the combination 125 with a stopper-head, of non-metallic refractory material, such as graphitic cement, provided with a conical neck and having an annular groove at the junction of said head and neck; of a metallic stopper shank including a U-shaped body having its bight imbedded 130

- in said head and its bifurcated ends projecting therefrom, through said neck; said bifurcated ends being provided with transversely extending holes in coaxial relation exterior 5 to said neck; the refractory material of said head being recessed between the bifurcations of said shank, to form a stopper rod socket.
7. In casting apparatus, the combination with a stopper-head, of non-metallic refractory material, provided with a neck and having an annular groove at the junction of said head and neck; of a metallic stopper shank including a U-shaped body having its bight imbedded in said head and its bifurcated 10 ends projecting therefrom, through said neck; said bifurcated ends being provided with transversely extending holes, in coaxial relation; the refractory material of said head being recessed between the bifurcations of said shank, to form a stopper rod socket.
10. In casting apparatus, the combination with a stopper-head, of non-metallic refractory material; of a metallic stopper shank including a U-shaped body having its bight imbedded in said head, and having transversely extending holes, in coaxial relation; the refractory material of said head being recessed 15 between the bifurcations of said shank, to form a stopper rod socket.
11. In casting apparatus, the combination with a stopper-head, of non-metallic refractory material; of a metallic stopper shank including a U-shaped body having its bight imbedded in said head, and having means arranged to detachably secure a stopper rod 20 between the bifurcations of said shank.
8. In casting apparatus, the combination with a stopper-head, of non-metallic refractory material, provided with a neck; of a metallic stopper shank including a U-shaped body having its bight imbedded in said head and its bifurcated ends projecting therefrom, through said neck; said bifurcated ends being provided with transversely 25 extending holes, in coaxial relation; the refractory material of said head being recessed between the bifurcations of said shank, to form a stopper rod socket.
9. In casting apparatus, the combination with a stopper-head, of non-metallic refrac-

In testimony whereof, I have hereunto signed my name at Coatesville, Pennsylvania, this twenty-second day of December, 1921.

SAMUEL McFARLAND.
